NAILING IMPLEMENT.

No. 392,963.

Patented Nov. 13, 1888.

UNITED STATES PATENT OFFICE.

HERBERT McCORNACK, OF McQUEEN, ASSIGNOR OF ONE-HALF TO E. A. McCORNACK, OF OAK GLEN, ILLINOIS.

NAILING IMPLEMENT.

SPECIFICATION forming part of Letters Patent No. 392,963, dated November 13, 1888.

Application filed May 26, 1888. Serial No. 275,211. (No model.)

To all whom it may concern:

Be it known that I, HERBERT McCORNACK, a citizen of the United States, residing at McQueen, in the county of Kane and State of Illinois, have invented a new and useful Improvement in Nailing Implements, of which the following is a specification.

My invention relates to a machine or implement for facilitating the operation of driving 10 nails by hand.

The object of my invention is to provide a portable implement by the use of which a supply of nails may be carried and fed by actuating the device to drive one at a time to the 15 driving mechanism, and by which the nailing operation may be performed without requiring the operator to stoop or assume any other than an upright position to perform the work.

My improvement may be used to advantage 20 in various connections in which driving of nails is practiced, as in nailing sidewalks, floors, and the like. It is especially useful for nailing shingles on roofs; and I have invented for use with it, when applied to this particular 25 purpose, a platform or stage, which will form the subject of a separate future application for Letters Patent, and though the stage affords a convenient adjunct for use in connection with my improved nailer the latter 30 does not depend for its advantageous application to nailing shingles on roofs upon such particular staging.

By the employment of my machine the shingles may all be laid ready for nailing, when 35 the operator, without stooping, may rapidly and accurately, by carrying and actuating the implement, drive nails along one row at a time of the shingles.

My invention consists in the general construction of my improved nailing implement, and it further consists in details of construction 40 and combinations of parts.

In the drawings, Figure 1 is a broken side elevation of my nailing implement; Fig. 2, a section through the feed-trough, taken on the 45 line 2 2 of Fig. 1, and viewed in the directions of the arrows; Fig. 3, a section taken on the line 3 3 of Fig. 1, viewed in the direction of the arrows and showing the slot in the head 50 at the lower end of the device into which the

feed-trough leads; Fig. 4, a broken longitudinal section of the implement, reduced, and showing details of its construction; Fig. 5, an enlarged view in side elevation of the lower end of the device, showing, externally, the 55 automatic feed-controlling mechanism; Fig. 6, a section taken on the line 6 of Fig. 5, viewed in the direction of the arrow and showing the internal mechanism for controlling the feed; Fig. 7, a similar view, broken, and showing 60 the feed-controlling finger in the position from which it is about to introduce a nail to the plunger; Fig. 8, an enlarged longitudinal sectional view of the upper portion of the plunger-rod and guide therefor, and Fig. 9 a bottom 65 view of the implement.

A is a hollow cylinder or tube, containing a plunger-rod, B, which extends beyond the cylinder, and may be provided at its projecting extremity with a handle, r, Fig. 4, and 70 below the handle on the rod is a stop, q, which, when the rod is forced into the cylinder in the manner and for the purpose hereinafter described, strikes against the capped end p, surrounded by a rubber washer, o, which in turn 75 is surmounted by a metal washer, o', the washers serving to take up the shock of the stroke of the plunger-rod in actuating the plunger, as hereinafter described. Within the cylinder A the rod B is surrounded toward its upper portion by a spiral spring, n, compressed between and secured at its extremities to collars m and m' within the cylinder, the former being an extension of the cap p and stationary, and the latter being secured to the rod 80 B and movable with it, (thus forming a guide,) whereby forcing the rod into the cylinder extends the spring, the resilience of which, in compressing to its normal condition, tends to force the plunger-rod upward out of the guide- 85 cylinder A.

The lower end of the cylinder A extends into a socket, l, at one end of a flat-sided rectangular, or substantially rectangular, oblong head, C, slotted from its base some distance 90 upward along the center of one edge or narrower side, as shown at x, the slot extending laterally into the central cylindrical aperture, k', which coincides with and forms a diametrically-reduced continuation of the ap- 95 100

erture k , which in turn coincides with and forms a continuation of the bore of the cylinder A, a shoulder, m^2 , being thus provided between the bores k and k' .

5 In the lower part of the bore of the cylinder A, and normally extending therefrom into the aperture or bore k , is a plunger-head, D', terminating in a plunger, D, narrower than the head, to fit the bore k' , into the upper end of which it normally extends, as shown in Fig. 4, being yieldingly held from further extension into the same by means of a spiral spring, n' , surrounding it, and confined between the lower end of the plunger-head D and shoulder m^2 . The lower end of the head C may be roughened, as indicated in Fig. 9.

E is the feed-trough chute, comprising the flaring portion h , which may be closed at one end, as shown at y , and open or slotted along 2c its converging edges, which are flanged, as shown at y' , and between the flanges y' are secured, to extend parallel to each other lengthwise of the part h and beyond the same, (see Fig. 1,) plates h' , secured at their ends, one 25 directly to the head C at one side of the slot x therein and the other to the inner face of an ear, i, on the head C at the opposite side of the slot x , whereby the feed-trough leads into the said slot and thus into the bore k' .

30 The position of the feed-trough with relation to the cylinder A and head C may be that shown, wherein it is secured to the cylinder by the wing i', to extend obliquely downward from the rear side of the implement and curve at 35 the portions of the plates h' , which extend beyond the flaring part h of the feed-trough around to the side slot, x , in the head C, the lower edges of the plates at the curve flaring slightly outward in opposite directions to 40 widen somewhat the space between them, and thus prevent binding of the nails in feeding. The feed-trough may, however, occupy any other suitable position with reference to the other parts, provided it extends obliquely 45 downward throughout its entire extent to feed the nails by gravity to the slot x .

The ear i (shown in Fig. 1) is provided near its upper end with a transverse slot, z, leading into the space between the plates h' , adjacent to the slot x , and in the slot z is pivoted a horizontal flat finger, F, bifurcated toward its extremity, which projects beyond the slot and flaring and slightly rounded toward its opposite extremity, which extends into and 55 blocks the space between the plates h' , being also provided at one corner with a curved lip, g, Figs. 6 and 7.

G is a bent lever fulcrumed to a side of the head C, as shown at f, Figs. 1 and 5, and extending thence obliquely downward between the prongs of the bifurcated finger F, and beyond the fulcrum the lever G is slotted, as shown at s, and extends, normally, obliquely upward around a pin, e, which projects from 60 the plunger-head D' through a vertical slot, s', in the side of the head C. Normally the pin e is at the upper extremities of the slots s

and s', being so maintained by the spring n' . Opposite the upper portion of the slot x the bore k' in the head C is hollowed out, as shown 70 at t, and in the hollow t is a light spring, d, normally extending into the path of the plunger D and serving a purpose hereinafter described.

The implement is used as follows: The chute 75 E is supplied with nails H by dropping them into it, when they extend, being guided by the flaring sides of the trough at their shanks, through the space between the plates h' , being supported at their heads, which extend across 80 the slot in the base of the flaring portion h and, beyond the latter, across the upper edges of the plates h' . When the feed-trough is filled, the nails extend from the closed end y to the finger F, which is normally in the position shown in Fig. 6. The implement is then held by the operator in the manner of holding a broom, with one hand grasping the handle. By forcing the rod B downward it strikes the plunger-head D', thereby forcing the plunger 90 to extend at its extremity to that of the bore k' , (the length of the stroke being gaged by the distance between the collar q and washer o,) and when a nail is in line with the plunger driving it into the object (shingle or the like) to be nailed. The first time of actuating 95 the plunger in the manner described, however, does not operate to bring the nail into position to be driven by it, since to start all the 100 nails are on the same side of the finger F while the latter is in the position shown in Fig. 6, and thus barred from entering the slot x . The downward stroke of the plunger turns (through the medium of the pin e, working in the slot s of the lever G) the finger F to the position 105 shown in Fig. 7, wherein, though still operating to hold back the nails, it is ready, in re-assuming the position shown in Fig. 6 by the return-stroke of the rod B and plunger, (produced by the resilient action of the springs n 110 and n' ,) to cause the lip g to engage with the nail at the end of the series or supply and admit it, by gravity, owing to the incline of the feed-trough, through the slot x into the bore k' , with its head in line with the plunger D. 115 The position last assumed by the finger F obviously stops the nails behind it. The nail thus admitted to the bore k' is prevented from falling lengthwise through the latter by the light spring d, which, however, is removed by 120 the plunger, which presses it into the hollow t in its downward stroke, and the spring d, besides arresting a nail as it enters the bore from the chute, performs the further function of adjusting it to a vertical position or into 125 line with the plunger in case it shall enter the bore at an angle from the vertical. Each downward stroke of the plunger after the first thus drives a nail, and its upward stroke actuates the finger F to admit automatically another 130 nail from the feed-trough to the plunger chamber or bore k' . Nailing, as will thus be seen, may, by the use of the implement, be carried on uninterruptedly by merely moving the

nailer on or over the object to be nailed in the line on which nails are to be driven and actuating the plunger from the handle *r*. The only stoppage occasioned is by the exhaustion of 5 the supply of nails in the feed-trough, requiring it to be replenished; but if the replenishing be attended to by an assistant of the operator there need be no interruption so far as the capability of continued action of the im- 10 plement is concerned.

Though I employ, for want of a better term to denote it in the description and claims, the term "cylinder" to designate the guide for the plunger, I do not intend thereby to confine myself to a cylindrical form for the part, as the latter may be of any suitable shape. It is also quite obvious that the rod *B* and plunger may be integral, though such a construction is not so desirable as that shown, and 15 other changes, such as would suggest themselves to those skilled in the art to which my invention relates, may be made in the details of construction without departing from the spirit of my invention.

20 It may be added that in case it shall be found advisable to cap the curved portion of the slot between the plates *h*, this may be done to prevent any tendency of the nails to become displaced by the pressure of the nail-supply behind them and jarring in the operation of the 25 implement.

What I claim as new, and desire to secure by Letters Patent, is—

1. In a hand nailing implement, the combination of a hollow cylinder, *A*, terminating in 30 a head, *C*, having bores *k* and *k'*, separated by a shoulder, *m*, and a slot, *x*, extending into

the bore *k'*, a spring plunger-rod, *B*, in the cylinder *A*, a spring-plunger, *D*, in the bore *k* and extending into the bore *k'*, and provided 40 with a plunger-head, *D'*, below the plunger-rod *B*, a chute, *E*, communicating with the slot *x* below the lower end of the plunger, with the latter in its normal position, and a spring, *d*, in a concavity, *t*, in the bore *k'* and normally ex- 45 tends into the path of the plunger, substantially as described.

2. In a hand nailing implement, the combination of a cylinder having a bore containing a reciprocating plunger, an inclined feed-trough, *E*, leading into the bore, a pivotal finger, *F*, bifurcated toward one end and provided with a lip, *g*, at its opposite end, which extends across the feed-passage, a pivotal slot-bent lever, *G*, engaging toward one end 50 with the finger, and a pin, *e*, extending from the plunger through a slot in the cylinder and engaging with the slot in the lever *G*, substantially as described.

3. A hand nailing implement comprising, 55 in combination, a cylinder, *A*, a reciprocating spring-plunger in the cylinder, a plunger-rod, *B*, in the cylinder and extending beyond the same, a spring, *d*, extending normally into the path of the plunger, an inclined feed-trough, *E*, a pivotal finger, *F*, provided with a lip, *g*, extending across the feed-passage, and a pivotal lever, *G*, engaging with the finger and actuated from the reciprocating plunger, substantially as described.

HERBERT McCORNACK.
